Primary Examiner — Susan Moon Lee(74) *Attorney, Agent, or Firm* — Sughrue Mion, PLLC(57) **CLAIM**

The ornamental design for a memory card, as shown and described.

DESCRIPTION

FIG. 1 is the perspective view of the memory card showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is rear perspective view thereof.

Broken lines and entirely unshaded portions contained within broken lines are not claimed. The dot dash lines in the figures represent an unclaimed boundary line and form no part of the claimed design.
